UNITED STATES PATENT OFFICE

2,558,073

HAIRCUTTING DEVICE

Lewis F. Clawson, Jr., Ramona, Calif.

Application October 25, 1948, Serial No. 56,275

2 Claims. (Cl. 30—30)

1

The present invention relates to a hair cutting device and it consists in the combinations, constructions and arrangements of parts herein described and claimed.

It is an object of the present invention to provide a hair cutting device which is simple in its construction and operation and yet effective and efficient in use.

Another object of the invention is the provision of a hair cutting device which makes use of the conventional razor blade.

Another object of the invention is the provision of a device of the character set forth in which simple means is provided for adjusting the position of the razor blade with the edges of tines forming a comb which is part of the invention.

Another object of the invention is the provision of a novel blade carrying device which forms a part of the invention.

Other and further objects of the invention will become apparent from a reading of the following specification taken in conjunction with the drawing, in which:

Figure 1 is an elevational view, partly broken away, of an embodiment of the invention,

Figure 2 is a sectional view taken along line 2—2 of Figure 1,

Figure 3 is a fragmentary elevational view of an element of the invention,

Figure 4 is a sectional view taken along line 4—4 of Figure 3,

Figure 5 is a sectional view taken along line 5—5 of Figure 3,

Figure 6 is an elevational view of an element of the invention,

Figure 7 is a side elevational view of Figure 6, and

Figure 8 is a sectional view taken along line 8—8 of Figure 6.

Generally there is provided a hair cutting device consisting of a body having teeth or tines upon either side thereof and having an integrally formed handle extending therefrom. Slidably and at an angle to the body there is provided a blade carrying member which is adapted to hold frictionally against the tines and in parallel relation thereto a conventional razor blade. When the device is in use, simple manipulation of the thumb of the user bearing against the blade carrying member will allow the blade to be placed at varying distances from the ends of the tines thereby allowing hair to be cut at varying lengths.

Referring more particularly to the drawing,

2

there is shown therein a hair cutting device consisting of a body 10 having integrally formed therewith an elongated handle 11. The body is formed along either side thereof with a plurality of spaced tines 12 and 13.

One side of the body is provided with an angularly extending relatively wide groove 14 having inwardly tapering edges 15 and slidably mounted in the groove 14 is a blade carrying member 16 having tapering edges 17 which intersect in the groove edges 15.

The inner face of the member 16 is provided with a pair of projections 18. The body is also provided with a pair of recesses 19 and 20 which are adapted to receive the projections 18.

In operation, it will be apparent that a razor blade 21 may be placed upon the blade holder 16 in such manner that the projections 18 extend through the conventional openings in the blade. Thereafter the holder may be inserted in such manner in the groove 14 that the edges 17 lie beneath the overhanging portions of the body 10, or, in other words, in such manner that the body of the blade holder is keyed and slidably in the body 10. The user of the device will grasp the handle 11 in his hand and by manipulating his thumb against the blade holder 16 may bring the edge of the blade 21 to or away from the edges of the tines or teeth 12, thereby allowing him to cut varying lengths of hair from his head.

While but one form of the invention has been shown and described herein, it will be readily apparent to those skilled in the art that many minor modifications may be made without departing from the spirit of the invention or the scope of the appended claims.

What is claimed is:

1. A device of the character described comprising a body having a key slot formed in one side thereof, tines formed in the longitudinal edges of the body, a handle formed integrally with the body at one end thereof, a blade holder having a key projection slidable in said key slot and a blade carried by the holder in parallel relation to the edges of the tines, said body having a pair of recesses and said holder having a pair of projections for mounting a conventional double-edge blade thereon and said projections extending into said recesses and said key slot being at an acute angle to the edges of the tines.
2. A device of the character described comprising a body, tines formed integrally at either side of the body, a handle integrally formed

55

with the body at one end thereof, a blade holder removably and slidably mounted on said body at an angle to the edges of the tines and a blade carried by the holder and having its cutting edge parallel to the edges of the tines, said body having a pair of recesses and said holder having a pair of projections for mounting a conventional double-edge blade thereon and said projections extending into said recesses.
